UNITED STATES PATENT OFFICE.

AUGUSTUS H. HEISEY, OF PITTSBURG, PENNSYLVANIA.

DESIGN FOR GLASS BOWLS.

Specification forming part of Design No. 7,493, dated June 16, 1874; application filed May 22, 1874.
[Term of Patent 7 years]

To all whom it may concern:

Be it known that I, AUGUSTUS H. HEISEY, of Pittsburgh, in the county of Allegheny and State of Pennsylvania, have invented a Design for a Glass Bowl, of which the following is a specification:

The nature of my design is fully represented in the accompanying drawings, of which—

Figure 1 is an elevation, and Fig. 2 a plan view of that portion of the bowl inverted which is above the line $x\ x$ of Fig. 1.

The body A of the bowl is semi-spherical in general form, the lower portion of which unites with a supporting column, B, which, below the line $y\ y$, gradually expands into a circular foundation-support, as shown at C.

The bottom portion of the body A of the bowl and a part of the column B form a hexa-

gon of concave sides, whose upper parts a are outwardly expanded upon the exterior lower portion of the body A of the bowl, each of the sides of the hexagon figure or form being connected to its adjoining fellow by arched lines, as at a^1 , on the body A, while the lower portion of the sides of the hexagon form terminate in reversed arched lines, as at a^2 , on the column B, as shown in Fig. 1.

What I claim as my invention is—

A design for a glass bowl, the supporting column B between the foundation-base and body of the bowl being in the form substantially as described and shown.

AUGUSTUS H. HEISEY.
